UNITED STATES PATENT OFFICE.

JAMES J. G. COOPER, OF JACKSONVILLE, FLORIDA.

BLOTTER-HOLDER.

1,272,388.

Specification of Letters Patent. Patented July 16, 1918.

Application filed March 30, 1917. Serial No. 158,714.

To all whom it may concern:

Be it known that I, JAMES J. G. COOPER, a citizen of the United States, residing at Jacksonville, in the county of Duval and 5 State of Florida, have invented certain new and useful Improvements in Blotter-Holders, of which the following is a specification.

This invention relates to stationary articles, and has more especial reference to 10 an improved blotter holder. It may be stated, that the principal object of the invention is to provide a blotter holding device which will prevent the misplacing of a blotter and will, at all times, support the 15 blotter in position available for instantaneous use.

Another important characteristic of the present invention, resides in the novel construction and arrangement of my improved 20 device, the same being so constructed as to permit rotation of the blotter holding arm, thereby permitting the blotter to be used in blotting any article within the radius of the arm, means being arranged upon said 25 arm whereby the same will be automatically returned to an out-of-the-way position when the blotter is released, consequently, rendering the same ready for subsequent usage.

Among the aims and objects of the invention may be recited, the provision of a device of the character mentioned, with a view 30 to compactness, and in which the number of parts are few, the construction simple, the cost of production small, and efficiency and 35 operation high.

The annexed drawings and the following description set forth in detail, certain construction embodying the invention, such disclosed means constituting, however, but one 40 of the various mechanical forms in which the principle of the invention may be used.

In said annexed drawings:—

Figure 1 is a side elevation of my improved blotter holding device,

45 Fig. 2 is a front elevation thereof, and

Fig. 3 is a fragmental detail partly in section showing the mounting of the rotatable blotter holding arm.

Referring now more particularly to the 50 drawings, wherein like reference numerals designate corresponding parts in the several views, it may be stated that the device comprises a base 1, upon which a stand 2, is mounted. A pocket 3 may be and 55 preferably is formed within the stand and serves in the capacity of an ink-well. To provide

for means whereby the blotter holding arm, which will be subsequently described, may be supported, an up-right standard 4 is arranged upon the stand 2 adjacent one side 60 thereof. It is to be noted, that the rear walls of the stand 2 and the standard 4 are beveled, for a purpose which will be hereinafter more fully described. A pivot pin 5 is arranged upon the upper extremity of the 65 standard 4 and rotatably receives a substantially U-shaped bracket 6, the said bracket having formed in the base portion thereof, a vertically disposed opening 7, into which the pivot pin 5 is inserted.

A blotter holding arm 8 being off-set intermediate its ends as at 9, is pivotally supported between the lateral portions of the bracket 6, by means of a cross pin 10, which is mounted within suitable openings therein. 75 The off-set portion 9 of the arm 8 is coiled upon itself, as at 11 and provides for means whereby the said arm may be pivotally supported upon the cross pin 10. By so mounting the blotter holding arm 8, it is obvious 80 that a compound movement thereof is afforded, inasmuch, as the same may be not only swung upwardly and downwardly upon the pivot pin 10 but may be also rotated, by means of the rotatable mounting of the 85 bracket 6 upon the pin 5. A weighted member 12 is affixed to one end of the arm 8 and will cause that member to be normally maintained in a substantially up-right position. As will be noted, the said weighted member 90 12, rests upon the lower portion of the beveled rear wall of the stand 2 and the lower portion of the arm 8 is permitted to be arranged in close relation to the rear wall of the stand and standard 4.

With a view to providing for means whereby a blotter may be secured to the remaining end of the arm 8, the same is preferably coiled at that point, as shown at 13, and receives through the convolutions thereof, a cord 14, one end of the same being knotted at 15, to prevent subsequent displacement thereof. To the remaining end 100 of the cord, there is secured a spring clasp 16 of any desirable construction, the said clasp having arranged thereupon an eyelet 17 through which the remaining end of the cord may be passed and knotted, as at 18, for an obvious purpose. A blotter 19 may be then engaged between the spring actuating jaws of the clasp 16 in any desired manner and when in such position, will hang 105 110

loosely from the coiled end 13 of the arm 8. A cross arm, comprising a wire 20, and having a portion intermediate its ends coiled about the blotter holding arm 8, as 5 at 21, provides for means whereby the blotter will at all times be maintained in proper position for use and will, serve to prevent rotation thereof.

In operating my improved device, the 10 blotter 19 is grasped by the user and moved downwardly into engagement with the article to be blotted. During such movement, the pivotally supported blotter holding arm 8 will be swung downwardly, raising the 15 weighted member 12 as affixed to the remaining end thereof. When swung downwardly, the arm may be then rotated, so that the blotter may be used upon any article within the radius thereof. Upon releasing the blotter, the arm will be again returned to its substantially up-right position, by means of the weighted member 12, thus, ready for subsequent usage. New 20 blotters may be readily substituted, by merely forcing the spring pressed jaws of the clasp 16 apart, whereupon the old blotter will be released and a new one may be then inserted therein and the jaws permitted to again close.

25 It will further be noted, upon referring carefully to Fig. 1 that the weighted member 12 normally rests against the inclined rear surface of the stand 2. As this surface is comparatively broad, as will be appreciated upon referring to Fig. 2, the arm will be held centrally and will be prevented from swinging to one side when not in use. If the arm were so supported as to not have its lower end engage a support, it is obvious 30 that an accidental hitting or the swinging of the blotter would tend to pull the arm around to one side so that when the user would desire to grip the blotter it would not be in a convenient position for use. However, 35 by having the weighted member 12 engaging the rear surface of the stand, as above specified, it is obvious the arc of movement described by a swinging of the arm to one side would be too small to allow the weighted member 40 to pass around the side portion of the stand and for this reason the weighted member will hold the arm against swinging accidentally to either side.

50 Other modes of applying the principle of

my invention may be employed instead of 55 those explained, change being made as regards the construction herein disclosed, provided the means stated by any of the following claims or the equivalent of such stated means be employed.

60 I therefore claim as my invention:

1. In a device of the class described, the combination of a stand having a standard projecting thereabove, the rear surface of the stand and standard being substantially 65 plane and inclined to the vertical, a supporting means rotatably mounted upon the upper end of said standard, a supporting arm pivotally mounted on said supporting means, said arm being capable of being 70 swung in a vertical plane, said arm being capable of being swung to either side by the rotation of said means upon said standard, said arm having a weighted rear end, said weighted end swinging into engagement 75 with the plane inclined surface of said stand when said arm is released, thus preventing the arm from accidentally swinging to either side when not in use.

2. In a device of the class described, the combination of a stand, said stand having a standard projecting thereabove, the rear surface of said stand and standard being substantially plane and inclined to the vertical, a pin extending from the upper end of said standard, a U-shaped bracket rotatably mounted upon said pin, a cross pin carried by said bracket, a supporting arm having an off-set portion intermediate its ends pivotally mounted upon said cross pin, thus allowing the arm to be swung vertically upon said bracket, while said bracket may rotate for permitting the arm to be swung to either side, a weight carried upon the rear end of said arm, said weight being adapted to swing the arm to an inoperative position when the same is released, thus causing the weight to bear upon the inclined plane surface of said stand thus preventing the arm from accidentally swinging to either 95 side when not in use.

100 In testimony whereof I affix my signature in presence of two witnesses.

JAMES J. G. COOPER.
